UNITED STATES PATENT OFFICE

OLE K. KJOLSETH, OF SCOTIA, NEW YORK, ASSIGNOR TO GENERAL ELECTRIC COMPANY,
A CORPORATION OF NEW YORK

UNCOUPLING DEVICE

Application filed December 14, 1928. Serial No. 325,951.

My invention relates to uncoupling devices, for locomotives or cars, of the type having two independently movable operating rods, and has for its object the provision of a device of this kind which is of simplified construction and which can be readily produced. I accomplish this by providing an uncoupling device comprising a pivotally supported coupling release lever having two crank arms extending therefrom, axially rotatable operating rods adapted to extend adjacent opposite sides of the car, and an arrangement connecting the operating rods to the lifting lever cranks for providing independent movement of the operating rods in actuating the release lever.

My invention will be more fully set forth in the following description referring to the accompanying drawing and the features of novelty which characterize my invention will be pointed out with particularity in the claims annexed to and forming a part of this specification.

In the drawing Fig. 1 is a perspective view of my uncoupling device applied to a locomotive or car, and Fig. 2 is a side elevation of my uncoupling device, the position to which the device is moved in uncoupling a locomotive or car being indicated in dotted lines.

Referring to the drawing I have shown my uncoupling device in connection with locomotive or car 10 having an end sill 11 and a coupling 12 which is provided with a vertically movable coupling pin 13 which is raised and lowered in the usual manner. The coupling pin 13 is raised and lowered by axially rotatable operating rods 14 extending adjacent the sides of the car which are supported on brackets 15 and 16 secured to the end sill 11, the operating rods being provided with depending handles 17 for convenience in actuating them.

It is desirable, particularly, on switching locomotives, which are usually provided with a platform on the front end thereof for brake-

men, that the operating rods 14 be operable independent of each other, for the reason that if a brakeman standing on one side raises the handle 17 when the coupling or uncoupling is done, the raising of the handle 17 on the other side might strike the brakeman standing thereon and cause him to lose his footing on the platform. In accordance with my invention, therefore, I connect the coupling 13 to the operating rods 14 by providing a coupling release lever 18 of substantially T-shape and support the coaxial portions thereof on brackets 19 secured to the end sill. The ends of the coaxial portions of the release lever extend beyond the brackets 19 and are bent upwardly at 20 to form cranks. The movable end of the release lever is connected to the coupling pin 13 by links 21 and the cranks 20 of the release lever are connected to the operating rods 14 by means which permits actuation of one of the operating rods independently of the other. In the particular construction illustrated, I do this by forming cranks 22 on the ends of the operating rods 14 which are retained in the desired relation to the bracket 16 by collars 23. The cranks 22 are connected to the cranks 20 by links 24 of such length that the cranks 20 and 22 are substantially parallel. The links 24 are pivotally connected at 25 to the cranks 20 and are pivotally connected to the cranks 22 by a cross-pin 26 which is slidable in an axially extending slot 27 formed in the links. By this construction when one of the levers 17 is actuated the coupling 13 will be raised by the connection including the crank 22, link 24, crank 20, release lever 18 and links 21, the position of the linkage being indicated in dotted lines in Fig. 2. At the same time the other lever 17 will remain in its lowered position because the cross-pin 26 in the end thereof will slide axially in the slot 27 formed in the link 24.

Modifications of the particular form of uncoupling device which I have disclosed will occur to those skilled in the art, so that I do

not desire my invention to be limited to the particular arrangement described except as it is set forth in the appended claims.

What I claim as new and desire to secure by Letters Patent of the United States, is:

5 1. An uncoupling device for locomotives or cars comprising a pivotally supported coupling release lever having two crank arms extending therefrom, axially rotatable operating rods adapted to extend adjacent opposite sides of the car and having crank arms thereon, and means including links connecting said operating rod cranks to said lifting lever cranks for providing independent movement of said operating rods in actuating said release lever.

10 2. An uncoupling device for locomotives or cars comprising a pivotally supported coupling release lever having two crank arms extending therefrom, axially rotatable operating rods adapted to extend adjacent opposite sides of the car and having crank arms thereon, and means connecting said operating rod cranks to said lifting lever cranks for providing independent movement of said operating rods in actuating said release lever, said means including links having a sliding joint connecting at one end and a pivotal connection at the other end.

15 3. An uncoupling device for locomotives or cars comprising a pivotally supported coupling release lever having two crank arms extending therefrom, axially rotatable operating rods adapted to extend adjacent opposite sides of the car and having crank arms thereon, and means connecting said operating rod crank to said lifting lever crank for providing independent movement of said operating rods in actuating said release lever, said means including links having a sliding pivotal connection at one end and a pivotal connection at the other end.

20 4. An uncoupling device for locomotives or cars comprising a coupling release lever of substantially T-shape, and having crank arms on the coaxial branches thereof, means for pivotally supporting said release lever for movement about said coaxial branches, axially rotatable operating rods adapted to extend adjacent opposite sides of the car and having crank arms thereon substantially parallel to the crank arms of said release lever, and means connecting said operating rod cranks to said lifting lever cranks for providing independent movement of said operating rods in actuating said release lever.

25 5. An uncoupling device for locomotives or cars comprising a coupling release lever of substantially T-shape, and having crank arms on the coaxial branches thereof, means for pivotally supporting said release lever for movement about said coaxial branches, axially rotatable operating rods adapted to extend adjacent opposite sides of the car and having crank arms thereon substantially

parallel to the crank arms of said release lever, and means connecting said operating rod cranks to said lifting lever cranks for providing independent movement of said operating rods in actuating said release lever, said means including links having a sliding joint connection at one end and a pivotal connection at the other end.

In witness whereof, I have hereunto set my hand this 13th day of December, 1928.

OLE K. KJOLSETH.
